[57] CLAIM

The ornamental design for an outdoor light fixture, substantially as shown and described.

DESCRIPTION

FIG. 1 is a perspective view of an outdoor light fixture showing my new design;

FIG. 2 is a top plan view thereof;

FIG. 3 is a bottom plan view thereof;

FIG. 4 is a front elevational view thereof, the back elevational view being the same in appearance as the front elevational view;

FIG. 5 is a side elevational view thereof, the opposite side being the same in appearance as the side shown;

FIG. 6 is a perspective view of an outdoor light fixture showing a second embodiment of my new design;

FIG. 7 is a top plan view of such second embodiment;

FIG. 8 is a bottom plan view of such second embodiment;

FIG. 9 is a front elevational view of such second embodiment, the back elevational view being the same in appearance as the front elevational view; and

FIG. 10 is a side elevational view of such second embodiment, the opposite side being the same in appearance as the side shown.
